UNITED STATES PATENT OFFICE

2,612,694

DRAFTING MACHINE

Francis E. Vaughan, Pasadena, Calif.

Application July 11, 1945, Serial No. 604,494

8 Claims. (Cl. 33—79)

1

My invention relates to a drafting machine comprising a fixed member clamped to a drawing board, an arm pivoted at one end to the fixed member, a second arm pivoted at one end to the moving end of the first arm, and a drafting head carried at the free end of the second arm and movable over the drawing board. The drafting head includes a protractor and a protractor arm provided with a vernier or witness point and with means for holding one or more rulers or straight edges which can be rotated about the protractor. As the drafting head is moved over the drawing board, orientation of the protractor is held constant either by some combination of pulleys and bands or by some combination of parallel arms. The protractor arm is rotatable with respect to the protractor and is adapted to be held firmly in any desired azimuth.

An object of my invention is to provide a micrometric control means in a drafting machine whereby one member in said machine can be moved slowly and under firm control through either large or small angles with respect to another member in said machine.

Another object of my invention is to provide the drafting head of a machine of the character described above with a micrometric protractor arm control, that is to say, micrometric control means is provided whereby the protractor arm can be moved slowly and under firm control through either large or small angles.

Another object of my invention is to provide a worm and gear mechanism operating between two members of a drafting machine for changing their angular relationship with respect to each other.

Another object of my invention is to provide a micrometric control means comprising a worm and gear mechanism operating between a protractor arm and a protractor.

Another object of my invention is to provide a means for readily engaging or disengaging the micrometric control means so that the member or protractor arm in said machine can be rotated under micrometric control or freely rotated as may be desired.

Another object of my invention is to provide the micrometric control means with over-center means, that is means whereby the worm is urged into engagement with the gear when the over-center means is in one position so as to eliminate lost motion, and to firmly urge the worm away from the gear when the over-center means is in the other position in order to eliminate the likelihood of accidental engagement.

2

Another object of my invention is to provide a worm and gear mechanism operating between two members of a drafting machine in which the gear is mounted on a shaft carrying one member and the worm is mounted so as to move with the other member, said worm being mounted on a support which is movable with respect to the gear, so that the worm can be moved into engagement with the gear or away from the gear as desired.

Another object of my invention is to provide a drafting machine with a micrometric control means, said micrometric control means being positioned just below the handle for ease of operation.

Another object of my invention is to provide a drafting machine in which a gear is mounted above the pulley and concentric therewith, and in which movable means are provided for engaging the gear.

Another object of my invention is to provide a drafting machine in which a gear is mounted above the pulley and in which a worm screw is mounted on a support carried by a shaft concentric with the pulley, and is adapted to engage the gear so that the members which are connected to the gear and worm screw, respectively, can be rotated either freely or under firm control.

Another object of my invention is to provide means for readily engaging and disengaging said worm screw from said gear.

Another object of my invention is to provide resilient means for urging the worm screw against the gear when the worm screw and gear are in engagement.

Another object of my invention is to provide a drafting machine in which the worm screw is mounted on a movable support and in such a manner that when the movable support is moved to one position, the worm screw will be in engagement with the gear, and that when the movable support is moved to another position, the worm screw will be clear of the gear.

My invention has many other objects, advantages, and features, some of which, with the foregoing, will be apparent from the following description and the accompanying drawings which are now considered to be preferred embodiments of the invention. It should be understood, however, that these particular embodiments of the invention are chosen for the purpose of exemplification, and I do not limit myself to the forms shown, since the invention, as set forth in the claims, may be embodied in a large plurality of forms.

Referring to the drawings:

Figure 1 is the plan view of a drafting machine of the pulley and band type embodying my invention.

Figure 2 is a plan view of the drafting head of the machine showing certain details of construction.

Figure 3 is a sectional view taken along the line 3—3 in Figure 2.

Figure 4 is a sectional view taken along the line 4—4 in Figure 2.

Figure 5 is a plan view showing details of the subplate carrying the worm, and the method by which it is mounted upon the handle plate.

Figure 6 shows a modification of my invention in which the gear is mounted on the inner shaft with the handle, and the worm screw is mounted on the outer shaft, the view corresponding to Figure 4 of the structure shown in Figures 1—5 inclusive.

Figure 7 is another view of the modification of my invention shown in Figure 6, the view corresponding to Figure 3 of the structure shown in Figures 1—5 inclusive.

Any conventional means can be used to hold the protractor in constant orientation as it is moved over the board. In the drawings, I have shown a band and pulley arrangement for illustrative purposes only.

Referring to the form of my invention shown in Figures 1 to 5, the numeral 11 indicates any conventional clamp for holding the drafting machine to a drawing board 12. The clamp 11 carries a pivot shaft rising perpendicularly to the board, to which is rigidly affixed a single groove pulley (not shown) which is engaged by a band 13. An arm 14 is pivoted to the shaft by a suspension head 15 in such a manner that it can be rotated about said shaft. At the other end of the arm 14 is a two groove pulley (not shown) which is mounted on the axis of articulation at 16 between the arms 14 and 17. The band 13 engages one groove of this pulley and a band 18 engages the other groove.

As shown in Figure 3, the other end of the arm 17 is connected to a pulley housing 19 in which is mounted a hollow shaft 20 by means of ball bearing 21. The hollow shaft 20 is provided with a flange 22 at its lower end and threads at its upper end. Also mounted on said hollow shaft 20 is a lock plate 23 and a pulley 24 which, together with the above-mentioned ball bearing 21, are held in position by means of nut 25. The lock plate 23 and the pulley 24 are adapted to be held together as a unit by means of screws 26. The band 18 engages the pulley 24. A gear 27 is firmly affixed to the upper end of the nut 25. Concentric with the hollow shaft 20 is the protractor 28 which can be engaged to rotate with the shaft 20 by a lock lever device 29 which locks the protractor 28 to the lock plate 23. Details of the lock lever device 29 are shown in Figure 4. From the foregoing it is clear that the gear 27 is fixed to the shaft 20; moreover, the protractor 28 is also fixed to the shaft 20 when the protractor 28 is locked to the lock plate 23.

As clearly shown in the drawings, a protractor arm 30 extends beneath the protractor 28 and a part of said protractor arm encircles the protractor, serving as a guard and bearing a witness point to indicate the angular position of the protractor arm relative to the protractor. Mounted upon the protractor arm 30 is the scale 31.

The protractor arm 30 is adapted to be rotated

with respect to the protractor 28. As an instance of this arrangement, disposed in the hollow shaft 20 is a smaller shaft 32, at the lower end of which are a flange 33 and a cross pin 34. The protractor arm 30 is designed to rotate with the shaft 32 by being pressed firmly down against the flange 33 in such a manner that the cross pin 34 is pressed into a slot 35 in the protractor arm. The upper end of the shaft 32 is threaded and a nut 36, screwed lightly down against the upper end of the hollow shaft 20, holds the protractor arm 30 up against the protractor 28, but permits said protractor arm 30 to be rotated with respect to said protractor 28 and the lock plate 23 to which said protractor may be locked.

Above the nut 36 is the handle plate 37 having a slot 38 similar to the slot 35 in the base plate, said slot 38 being provided to receive a cross pin 39 through the shaft 32. A nut 40 acts as a lock to hold the nut 36 and the handle plate 37 firmly upon the shaft 32. A handle 41 is fastened to the upper side of the handle plate 37 by means of screws 42, by means of which the protractor arm 30 is adapted to be rotated.

Micrometric control means is provided whereby the protractor arm 30 can be moved slowly and under firm control with respect to the protractor 28 through either large or small angles, together with means for readily engaging or disengaging the micrometric control means so that the protractor arm 30 can be rotated under micrometric control or freely rotated as may be desired. As an instance of this arrangement, as shown in Figures 2 and 3 and in somewhat greater detail in Figure 5, a subplate 43 is fastened to the under side of the handle plate 37. This subplate is designed to rotate through a small arc about a flanged bushing 44, which is held firmly against the handle plate 37 by means of the screw 45. A spring washer 46 between the flange of the bushing 44 and the subplate 43 holds the latter against the handle plate 37 and eliminates vertical play. A flanged stop bushing 47 passes through a slot 48 in the subplate 43 and is held firmly against the handle plate 37 by means of the stop bushing screw 49. The purpose of this arrangement is to limit the arc through which the subplate 43 can be rotated about the bushing 44; moreover, the flange of the bushing 47 tends to hold the subplate 43 close to the handle plate 37.

Depending from the subplate 43 are two lugs 50 and 51 provided with holes 52 and 53, through which passes a shaft 54 upon which is fixed a worm 55 between the lugs 50 and 51. A spring washer 56 on the shaft 54, and interposed between one end of the worm 55 and the lug 50, is provided to eliminate end play of the worm between the lugs. To the outer end of the shaft 54 is fixed a knurled thumbpiece 57, by means of which the shaft 54 and the worm 55 can be rotated. The thumbpiece 57 can also be used to rotate the subplate 43 through its small arc about the bushing 44; that is to say, it can be used to engage and disengage the worm 55 and the gear 27. One limit of the arc, as determined by the slot 48, is such that the worm 55 will clear the gear 27 when the subplate is pressed as far as possible outward and away from the center of the handle plate 37. The other limit of the arc, as determined by the slot 48, permits the worm 55 to engage firmly the gear 27 when the subplate is moved as far as possible toward the center of the handle plate 37; indeed, the slot 75 permits slightly greater motion than the gear

permits, so that firm engagement is insured even after some wear has developed between the worm 55 and the gear 27.

An angular projection 58, with a somewhat rounded point, is provided at the end of sub-plate 43 remote from bushing 44. A spring 59 is provided to hold the subplate 43 in one or the other of its extreme positions. One end of the spring 59 is fastened to the handle plate 37 by means of the screws 60 and 61. The free end of the spring 59 is provided with an angular projection 62, with a somewhat rounded point, similar to the projection 58 on the subplate 43, directly opposite the mid-position of the projection 58 as the subplate moves through its restricted arc; that is to say, it lies opposite the position midway between the two extreme positions of the projection 58 as the subplate 43 is moved through its limited arc about the bushing 44. It should be noted particularly that on either side of the mid-position of the subplate 43 the force components of the spring 59, transmitted by the inclined surfaces of the projections 58 and 62 along the path of the point of the projection 58, are in opposite directions. It is clear that this arrangement provides an over-center mechanism whereby on one side of the center the subplate 43 is pressed toward one limit of its restricted arc and on the other side of the center said subplate is pressed toward the other limit of the arc; that is to say, it provides means for pressing the worm in engagement with the gear 27 on the one hand, and for holding it clear of the gear 27 on the other hand.

In actual use the drafting machine is affixed to the board 12 by means of the anchor 11, as in Figure 1, the drafting head being adapted to be moved over the board while the orientation of the protractor 28 is maintained through the pulley and band arrangement. The orientation of the protractor arm 30 with respect to the protractor 28 is maintained through the worm 55 and gear 27 mechanism. During much of the ordinary routine work, the orientation of the protractor arm 30 is such that the ruler thereon is parallel to two sides of the drawing board and to some of the primary lines of the drawing itself. At the same time the protractor reading is zero. As it becomes desirable to draw lines in the directions thus indicated at various positions on the board, the drafting head can be moved across the board by taking hold of the handle 41 or of the ruler 31 and pushing it into position. During this procedure it is usually desirable to have the worm 55 and the gear 27 in engagement with each other.

If it is desired to draw a line making some desired angle with the direction indicated by the zero reading of the protractor, the left hand is placed upon handle 41 and the thumb piece 57 is pressed with the index finger so as to disengage the worm 55 from the gear 27. The protractor arm can now be rotated freely so as to set off the desired reading on the protractor 28, the rotation being accomplished either by means of the handle 41 or by taking hold of the scale 31. When the protractor arm has been rotated to approximately the desired position, the thumb piece 57 is pressed with the thumb of the left hand so as to engage the worm 55 with the gear 27. The protractor arm 30 can then be brought into the exact position desired by rotating the thumb piece 57 by means of the thumb and index finger of the left hand.

By making the gear 27 with a special number of teeth the worm and gear arrangement shown becomes an effective indexing mechanism for quickly setting off some of the most frequently used angles. For example, providing the gear 27 with 72 teeth affords certain advantages. With the worm 55 and a gear 27 having 72 teeth, in engagement with each other, rotate the thumb piece 57 until the protractor reading is zero or any multiple of 5 degrees. Now press the thumb piece 57 so as to disengage the worm 55 and the gear 27; rotate the protractor arm to approximately the desired angle, 30 degrees for example; firmly press the thumb piece 57 so as to engage the worm 55 and the gear 27. The protractor reading will now be 30 degrees. In a similar manner, the protractor arm can be brought readily to any angular position represented by a multiple of 5 degrees. Obviously, the gear could be made with some other number of teeth to provide a different selection of angles.

In the modification of my invention shown in Figures 6 and 7, the gear is mounted on the inner shaft 32 and is connected to the protractor arm 30 and the worm screw is mounted on the outer shaft 20 and connected to the protractor 28. The worm screw is so mounted on the outer hollow shaft 20 that it may be readily engaged or disengaged from the gear so that the protractor arm 30 can be rotated under micrometric control or freely rotated as may be desired.

As an instance of this arrangement, a gear 65, a spacer 66, and a handle plate 61, are fastened together by screws 68 so as to comprise a mechanical unit. This unit is mounted on the shaft 32 by means of nuts 69 and 70, and the pin 71. A worm screw 72 is mounted on a sub-plate 73 carried on a support 74 which is mounted on the hollow shaft 20 by means of nut 25. The subplate 73 may be movably mounted upon the support 74 in precisely the same manner that the subplate 43 is movably mounted upon the handle plate 37. The construction of this modification of my invention below the support plate 74 may be exactly the same as the construction of the form of my invention shown in Figures 1 to 5.

Obviously the operation of this form of my invention is essentially the same as the operation of the form of my invention shown in Figures 1 to 5 and will therefore not be repeated herein.

From the foregoing description take in connection with the accompanying drawings, the uses, advantages, and operation of the drafting machine of my invention will be readily understood by those skilled in the art to which the invention appertains. While I have described the principle of operation together with the forms of my invention which I now consider to be the best embodiments thereof, I desire to have it understood that the machine shown is merely illustrative and that the invention is not to be limited to the details disclosed herein, but is to be accorded the full scope of the appended claims.

I claim:

1. In a drafting machine of the pulley and band type the combination of: a pulley movably mounted over a flat surface while its orientation with respect to said flat surface is maintained, a hollow shaft which is fixed to said pulley and concentric therewith, a scale supporting member positioned below said pulley and having a second shaft fixed thereto which extends through said

pulley and said hollow shaft and which is concentric therewith and rotatable relative thereto; a handle on the upper end of said second shaft; a gear fixed against rotation relative to one of said shafts and positioned concentrically of such shaft between said pulley and said handle; a support carried by the other of said shafts; a third shaft rotatably mounted on said support and extending laterally with respect to said second shaft above said pulley and adjacent said handle; and a worm screw fixed to said third shaft for engagement with said gear to control relative rotation of said pulley and said scale supporting member; said support and said third shaft being movable to engage and disengage said worm screw and gear.

2. In a drafting machine of the pulley and band type, the combination of: a pulley movably mounted over a flat surface while its orientation with respect to said flat surface is maintained, a protractor having a hollow shaft fixed thereto which is fixed to said pulley; a protractor arm positioned below said pulley and having a second shaft fixed thereto which extends through and is concentric with said first shaft and rotatable relative thereto, a handle on the upper end of said second shaft; a gear fixed against rotation relative to one of said shafts and positioned concentrically of such shaft between said pulley and said handle; a support carried by the other of said shafts, a third shaft rotatably mounted on said support and extending laterally with respect to said second shaft above said pulley; and a worm screw fixed to said third shaft for engagement with said gear to control relative rotation of said pulley and said protractor arm; said support and said third shaft being movable to engage and disengage said worm screw and gear and means for retaining said support and said third shaft in either position of engagement or disengagement of said worm screw with said gear.

3. In a drafting machine of the pulley and band type, the combination of: a pulley movably mounted over a flat surface while its orientation with respect to said flat surface is maintained, a protractor below said pulley having a first shaft fixed thereto which extends through and is fixed to said pulley, a protractor arm positioned adjacent said protractor and having a second shaft fixed thereto which is concentric with said first shaft and rotatable relative thereto, a handle on the upper end of said second shaft; a gear fixed against rotation relative to one of said shafts and positioned concentrically of such shaft between said pulley and said handle; a support carried by the other of said shafts, a third shaft rotatably mounted on said support and extending laterally with respect to said second shaft above said pulley; and a worm screw fixed to said third shaft for engagement with said gear to control relative rotation of said pulley and said protractor arm; said support and said third shaft being movable to engage and disengage said worm screw and gear.

4. In a drafting machine of the pulley and band type, the combination of: a pulley movably mounted over a flat surface while its orientation with respect to said flat surface is maintained through mechanical linkage to said flat surface; a first shaft of tubular form concentric with said pulley and maintaining orientation with respect thereto; a second shaft passing through said pulley and said first shaft and rotatable with respect thereto; a scale supporting member affixed to the lower end of said second shaft; a handle

affixed to the upper end of said second shaft; a gear affixed concentrically upon one of said shafts and positioned between said pulley and said handle; a support carried by the other of said shafts, a third shaft rotatably mounted on said support and extending laterally with respect to said second shaft above said pulley and adjacent said handle, and a worm screw fixed to said third shaft for engagement with said gear to control relative rotation of said pulley and said scale supporting member; said support and said third shaft being movable to engage and disengage said worm screw and gear.

5. In a drafting machine of the pulley and band type, the combination of: a pulley movably mounted over a flat surface while its orientation with respect to said flat surface is maintained, a hollow shaft which is fixed to said pulley and concentric therewith; a scale supporting member positioned below said pulley and having a second shaft fixed thereto which extends through said pulley and said hollow shaft and which is concentric therewith and rotatable relative thereto, a handle on the upper end of said second shaft; a gear fixed against rotation relative to said hollow shaft and positioned concentrically of such shaft between said pulley and said handle; a support carried by said handle, a third shaft rotatably mounted on said support and extending laterally with respect to said second shaft above said pulley; and a worm screw fixed to said third shaft for engagement with said gear to control relative rotation of said pulley and said scale supporting member; said support and said third shaft being movable to engage and disengage said worm screw and gear.

6. In a drafting machine of the pulley and band type, the combination of: a pulley movably mounted over a flat surface while its orientation with respect to said flat surface is maintained, a protractor below said pulley having a first shaft fixed thereto which extends through and is fixed to said pulley; a protractor arm positioned adjacent said protractor and having a second shaft fixed thereto which is concentric with said first shaft and rotatable relative thereto, a handle on the upper end of said second shaft; a gear fixed against rotation relative to said first shaft and positioned concentrically of such shaft between said pulley and said handle; a support carried by said second shaft, a third shaft rotatably mounted on said support and extending laterally with respect to said second shaft above said pulley; and a worm screw fixed to said third shaft for engagement with said gear to control relative rotation of said pulley and said protractor arm; said support and said third shaft being movable to engage and disengage said worm screw and gear.

7. In a drafting machine of the pulley and band type, the combination of: a pulley movably mounted over a flat surface while its orientation with respect to said flat surface is maintained, a protractor below said pulley having a first shaft fixed thereto which extends through and is fixed to said pulley, a protractor arm positioned adjacent said protractor and having a second shaft fixed thereto which is concentric with said first shaft and rotatable relative thereto, a handle on the upper end of said second shaft; a gear fixed against rotation relative to said second shaft and positioned concentrically of such shaft between said pulley and said handle; a support carried by said first shaft, a third shaft rotatably mounted on said support and extending laterally with re-

spect to said second shaft above said pulley, and a worm screw fixed to said third shaft for engagement with said gear to control relative rotation of said pulley and said protractor arm, said support and said third shaft being movable to engage and disengage said worm screw and gear.

8. In a drafting machine of the pulley and band type the combination of: a pulley movably mounted over a flat surface while its orientation with respect to said flat surface is maintained, a hollow shaft which is fixed to said pulley and concentric therewith, a scale supporting member positioned below said pulley and having a second shaft fixed thereto which extends through said pulley and said hollow shaft and which is concentric therewith and rotatable relative thereto, a handle on the upper end of said second shaft, a gear fixed against rotation relative to said second shaft and positioned concentrically of such shaft between said pulley and said handle, a support between said pulley and said handle, a support carried by said hollow shaft, a third shaft ro-

tatably mounted on said support and extending laterally with respect to said second shaft above said pulley, and a worm screw fixed to said third shaft for engagement with said gear to control relative rotation of said pulley and said scale supporting member, said support and said third shaft being movable to engage and disengage said worm screw and gear.

FRANCIS E. VAUGHAN.
